UNITED STATES PATENT OFFICE.

JAMES H. WEBB, OF ADA, INDIAN TERRITORY.

BROOM-HEAD.

SPECIFICATION forming part of Letters Patent No. 690,495, dated January 7, 1902.

Application filed July 25, 1901. Serial No. 69,717. (No model.)

To all whom it may concern.

Be it known that I, JAMES H. WEBB, a citizen of the United States, residing at Ada, Chickasaw Nation, Indian Territory, have 5 invented a new and useful Broom-Head, of which the following is a specification.

This invention relates to broom-heads, and has for its object to present a simple and thoroughly efficient device which may be 10 readily adapted for holding either broom-corn to constitute a broom, or rags, shucks, or other material suited for use as a mop.

The invention consists, generally stated, in a frame provided at one end with an adjustable handle-socket and at the opposite end with a clamp for engaging the substance to be carried by the head, one member of the clamp forming an integral part of the head and the other member of the clamp being de- 20 tachable to facilitate insertion within the head of the substance to be carried thereby.

Other and salient features of the invention reside in means for effecting the ready clamping of the material within the head, means 25 for preventing loosening or rocking of the detachable clamp member, and means to hold the detachable clamp member against lateral movement with relation to the fixed member.

With these and other objects in view, as 30 will appear as the nature of the invention is better understood, the same consists in the novel construction and combination of parts of a broom-head, as will be hereinafter fully described, and specifically pointed out in the 35 claims.

In the accompanying drawings, forming a part of this specification, and in which like numerals of reference indicate corresponding parts, I have illustrated a form of embodiment of my invention capable of carrying my ideas into effect, it being understood that the elements herein exhibited may be varied or changed as to shape, proportion, and exact manner of assemblage without departing 45 from the scope of my invention, and in the drawings—

Figure 1 is a view in perspective of a broom-head characterized by my invention, the same having associated with it in this instance a 50 bunch of broom-straw, this being indicated by dotted lines. Fig. 2 is a view in vertical transverse section. Fig. 3 is a view in per-

spective of the detachable clamp member. Fig. 4 is a horizontal sectional view taken on the line 4 4, Fig. 1.

Referring to the drawings, and particularly to Fig. 1 thereof, I have exhibited a form of embodiment of my invention, the same comprising two side pieces 1, the upper ends of which are curved toward each other and then 55 at right-angles to the curved portion to present two lips or projections 2, between which works the broom-socket 3, the same in this instance being a hollow T-shaped structure, the head of which is fixed between the lips 2 60 and is held assembled therewith by a bolt 4, carrying a nut 5, by which the lips may be securely clamped against the head of the socket at any desired angle to the broom-head, as 65 will be hereinafter more fully pointed out.

The side pieces 1, adjacent to the curved insets, are held assembled by plates 6, the outer ends of which are bent at right angles to their length, as at 7, to bear against the outer surface of the side pieces, the offset 7 70 thus presented being held associated with the side pieces in any preferred manner, as by being soldered or riveted thereto. The two plates 6 when positioned as shown constitute a butt-socket for receiving the butts of the 75 broom-corn when the head is employed as a broom and under all conditions constitute braces for rendering the upper portion of the head firm and rigid. The lower extremities of the side pieces 1 have rigidly secured to 80 them a plate 8, constituting the fixed member of the clamp for holding the material employed within the broom-head, this fixed member being in this instance held associated with the side pieces 1 by having its ends 85 bent at right angles to its length to form offsets 9, these to be associated with the side pieces in any preferred manner, as by being 90 soldered or riveted thereto.

The detachable clamp member 10, which 95 coöperates with the fixed clamp member 8 for holding the broom-corn or other substance in the head, comprises a plate having its ends bent at right angles to its length to present two offsets 11, that bear against the outer 100 sides of the arm 1, as clearly shown in Fig. 4, and thereby prevent any lateral movement of the member 10 with relation to the said arms. Rigidly secured to the clamp member

10 at such distance from the offsets 11 as will permit insertion therebetween of the side pieces 1 are two arms 12, which are to be of such length that when the clamp member 10 is associated with the clamp member 8 they will project within the butt-socket, and thereby securely hold the clamping member against any rocking movement resulting from the pressure applied to the broom-straw 10 or other material under the operation of the device. Each of the two clamp members 8 and 10, respectively, is provided with two openings 13, through which pass bolts 14, carrying nuts 15, to effect the clamping together of the two 15 members, and while in this instance I have shown but two of these bolts it will be obvious that a greater number may be used and still be within the scope of my invention.

When the broom-head is to be used for 20 holding the broom-straw, the two nuts 15 are removed from the bolts 14, and the bolts are then removed. The clamp member 10 is then detached and a bunch of straw of the required bulk is placed between the side 25 pieces 1 with their butts housed in the butt-socket. The detachable clamp member is then placed in position, the bolts are inserted through the opening 13 in the two members, and the nuts 15 are then securely 30 seated in place. To utilize the head for accommodating rags where a mop is employed or for any other substance suited to constitute a mop or a whitewash-brush, the same procedure is observed as to the manner of securing it in place within the head, and where 35 the head is to be used for housing a material to be used as a mop the nut 5 is loosened and the broom-socket, and with it the handle, is turned to the angle best suited to the user, 40 after which the nut is again tightened.

From the foregoing description it will be seen that while the device of this invention is exceedingly simple in construction it combines in an effective manner all those elements that are requisite for performing the 45 functions for which the device is designed; further, all of the parts are capable of being

made by an ordinary mechanic, and this dispenses with the employment of intricate stamping or cutting mechanism for producing the parts. The cost of production will be so slight as to permit of the article being sold at a price that will appeal to every householder.

Having thus fully described my invention, 55 what I claim as new, and desire to secure by Letters Patent of the United States, is—

1. A broom-head comprising a frame provided at one end with a handle-socket, at the opposite end with a clamp and intermediate 60 of its ends with a butt-socket, one member of the clamp being rigidly secured to the head and the other member being detachable therefrom to permit insertion within the head of the substance to be carried thereby, and 65 means for effecting rigid assemblage of the clamp members.

2. A broom-head comprising a frame provided at one end with a handle-socket, at the other end with a two-part clamp and intermediate 70 of its ends with a butt-socket, one member of the clamp being provided with arms to fit within the butt-socket, and means for effecting rigid assemblage of the clamp members.

3. A broom-head comprising a frame composed of two parts, an adjustable handle-socket carried by one end of the frame, a butt-socket located adjacent to the handle-socket and holding the two members of the 80 frame assembled, a clamp member carried by the other end of the frame member, a detachable clamp member having arms to project within the butt-socket, and bolts passing through the two-clamp members for holding 85 the same rigidly assembled.

In testimony that I claim the foregoing as my own I have hereto affixed my signature in the presence of two witnesses.

JAMES H. WEBB.
